UNITED STATES PATENT OFFICE.

JOHN J. ENNIS AND WILLIAM T. HOHNHORST, OF COVINGTON, KENTUCKY.

DESIGN FOR A METAL DOOR-MAT.

42,380.

Specification for Design.

Patented Apr. 2, 1912.

Application filed December 4, 1911. Serial No. 663,960. Term of patent 3½ years.

To all whom it may concern:

Be it known that we, JOHN J. ENNIS and WILLIAM T. HOHNHORST, citizens of the United States, residing at Covington, in the county of Kenton and State of Kentucky, have jointly invented a new, original, and ornamental Design for a Metal Door-Mat, of which the following is a specification, reference being had to the accompanying drawing, forming a part thereof.

Our new, original and ornamental design

for a metal door mat is shown in the accompanying drawing, in which the figure is a plan view of the metal door mat.

We claim:

The ornamental design for a metal door mat, as shown.

JOHN J. ENNIS.

WILLIAM T. HOHNHORST.
